UNITED STATES PATENT OFFICE.

CHARLES HANSEL, OF ROCHESTER, NEW YORK.

MEANS FOR SUPPORTING SWITCH AND SIGNAL APPARATUS AND THE LIKE.

No. 803,532.

Specification of Letters Patent.

Patented Oct. 31, 1905.

Application filed April 16, 1904. Serial No. 203,529.

To all whom it may concern:

Be it known that I, CHARLES HANSEL, a citizen of the United States, and a resident of Rochester, in the county of Monroe and State 5 of New York, have invented certain new and useful Improvements in Means for Supporting Switch and Signal Apparatus and the Like, of which the following is a specification.

This invention relates to means for supporting switch and signal apparatus, apparatus for operating crossing-gates, bridge-locks, and the like.

It consists in the mechanism hereinafter described and claimed.

15 In the drawings, Figure 1 is a top plan view of an apparatus embodying this invention. Fig. 2 is an elevation of the same device shown in Fig. 1, parts being broken away to exhibit construction. Fig. 3 is an end elevation of 20 the same device. Fig. 4 is a cross-section on the line 4-4 of Fig. 3. Fig. 5 is an enlarged cross-section on the line 5-5 of Fig. 1. Fig. 25 6 is a top plan view of a modified form of this invention. Fig. 7 is a side elevation of the same. Fig. 8 is a vertical section on the line 8-8 of Fig. 7. Fig. 9 is a top plan view of a bell-crank support embodying this invention, and Fig. 10 is an elevation of the same.

In the drawings, 1 is a pillar, preferably of 30 molded concrete. One or any desired number of these pillars may be employed in combination, as hereinafter set forth. The pillars may have any suitable form. A useful form is shown in Figs. 2, 3, and 4.

35 The top of each pillar 1 is slightly beveled in order to fit tightly in a cap 2, which carries the supporting apparatus for pipe-carriers and like devices. This cap 2 is adapted to be fastened to the pillar 1 by means of an expanding-bolt 3, passing through a perforation 4 in the top of the cap and into a socket 5 in the pillar. Where it is desirable to strengthen the concrete pillar, a tube 6 is often cast into it, and the expanding-bolt 3 engages in this 45 tube. On each cap 2 is placed a support or table 7, on which pipe-carriers, &c., may be fastened, and where it is desirable to arrange said supports or tables so as to be connected together each support at the end is provided 50 with a recurved or hooked portion 8, so that when two or more like tables or supports 7 are brought together end to end, as shown in Figs. 1 and 2, the hooks 8 stand back to back, and a C-shaped fastener 9 is driven on the 55 two hooks, so that it interlocks with them and

fastens them permanently together. The hooks may be of the full width of the tables for greater solidity.

Where pipe-carriers are set upon the tables, the tables are made with suitably-formed edges 60 10, preferably projecting, rounded, and parallel, and the pipe-carriers are made with sides or standards 11, each of which has a portion fitting upon the top of the table 7 and ends 12 fitting over the edges 10 of the tables. In 65 this way pipe-carriers having any number of pipe-rollers 13 may be made by the use of a series of identical tables 7 and the desired number of identical standards 11. The sides or standards 11 may be fastened together at 70 the top by bolts 14, carrying, if desired, anti-friction-rollers 15.

A modified form of this device is shown in Figs. 6, 7, and 8, in which the sides or standards 16 for a pipe-carrier roller 17 may be 75 manufactured of sheet metal. The lower ends of the two identical side pieces are turned inward and meet each other and are then turned over and backward to form hooks 18, which are fastened together by means of a C-shaped 80 piece 19, whose edges fit into the hooks 18 and holds them tightly together. The ends of the connecting-piece 19 are then shaped or bent to clasp the edges 10 of the table.

From the elements above mentioned— 85 namely, the duplicate pillars, the duplicate supports upon the pillars, and the duplicate standards, &c., upon the support—it is clear that a foundation of any size and with any number of standards may be constructed from 90 these units, not requiring, as heretofore, special sizes of supports for each new foundation.

Instead of the table 7 (shown in Figs. 1 to 8) the cap 2 may carry a table or support 20, as shown in Figs. 9 and 10, which is grooved, 95 as at 21, in order to take the head of a bolt 22, whereby a support 23 for a bell-crank 24, compensator, or support for devices of the class mentioned above may be carried on two pillars 1. The cap 2 in this case is held to 100 the pillar 1 by the expanding-bolt 3, as hereinbefore described.

The pillars 1 are set in the ground and may be fastened together at their lower ends by a strut or brace 25, Fig. 2.

105 As shown, the top of the pillar 1 is round and slightly conical. The cap 2 fits on the top of the pillar, and the fastening or bolt is central to the pillar and the cap, and thus the cap may be turned around the bolt. By this 110

means the caps 2 may be alined both with reference to two or more caps and also with reference to the lines of pull of the operating mechanism.

5. What I claim is—

1. In an apparatus of the class described, a pillar, a cap therefor rotatable on the top of the pillar, means for fastening the pillar and the cap non-rotatably together, and a support

10 on said cap adapted for fastening a device of the class described thereto.

2. In an apparatus of the class described, a pillar having a socket fitted therein, a cap therefor, an expanding-bolt fitting in said

15 socket for fastening the cap upon the pillar, and a support upon said cap having projecting edges, and a standard adapted to fit upon and clasp said projecting edges.

3. In an apparatus of the class described, a pillar, a cap therefor, means for fastening the

20 pillar and cap together, a support on said cap adapted for fastening devices of the class described thereto, a like support, both said supports having hooked meeting edges, and C-

25 shaped fasteners fitting upon said hooked edges.

4. In an apparatus of the class described, a pillar, a cap therefor, means for fastening the pillar and cap together, a support on said cap

30 adapted for fastening devices of the class described thereto, a like support, both supports having hooked meeting edges, and C-shaped fasteners fitting upon said hooked edges, and a series of standards adapted to fit upon said

35 supports.

5. In an apparatus of the class described, a pillar, a cap therefor, means for fastening the pillar and cap together, a support on said cap adapted for fastening devices of the class de-

40 scribed thereto, a like support, both supports having hooked meeting edges, and C-shaped fasteners fitting upon said hooked edges, and a series of identical standards adapted to fit upon said supports.

45 6. In an apparatus of the class described, a pillar, a cap therefor, means for fastening the pillar and cap together, a support on said cap, a pair of standards adapted to be fastened to said support, and means for fastening said

50 standards together.

7. In an apparatus of the class described, a pillar, a cap therefor, means for fastening the pillar and cap together, a pair of standards,

and means for fastening said standards together and to said support.

55

8. In an apparatus of the class described, a pillar, a cap therefor, means for fastening the pillar and the cap together, a support on said cap, a pair of standards having hooked meeting edges, and a C-shaped fastener fitting 60 upon both hooked edges and adapted to fit upon and clasp said support.

9. In an apparatus of the class described, a pillar, a cap therefor, means for fastening the pillar and the cap together, a support on said 65 cap, a like support, both said supports having hooked meeting edges, C-shaped fasteners fitting upon said hooked edges, a pair of standards adapted to be fastened to a support and having hooked meeting edges, and a C- 70 shaped fastener fitting upon both hooked edges and adapted to fit upon and clasp said support.

10. In an apparatus of the class described, a pillar, a cap therefor fitting on the top of the 75 pillar, and means, around which the cap may be turned, for fastening the pillar and the cap non-rotatably together.

11. In an apparatus of the class described, a pillar having a round top, a cap fitting thereon, and a fastening central to the pillar and cap for fastening them non-rotatably together. 80

12. In an apparatus of the class described, a pillar having a conical top, a cap fitting thereon, and a fastening central to the pillar and 85 cap, and around which the cap may be turned, for fastening them non-rotatably together.

13. In an apparatus of the class described, a support, a table thereon having projecting edges, and a standard having hooked portions 90 adapted to fit upon and clasp said projecting edges.

14. In an apparatus of the class described, a support, and a table thereon having rounded projecting edges, and a standard having C- 95 shaped edges adapted to fit upon and clasp said rounded projecting edges.

15. In an apparatus of the class described, a support, a table thereon having projecting parallel edges, and a standard having hooked 100 portions adapted to fit upon and along and to clasp said edges.

CHARLES HANSEL.
